BY S. W. Webster
ATTORNEY

UNITED STATES PATENT OFFICE

ADIEL Y. DODGE, OF SOUTH BEND, INDIANA, ASSIGNOR TO BENDIX BRAKE COMPANY,
OF SOUTH BEND, INDIANA, A CORPORATION OF ILLINOIS

BRAKE

Original application filed April 17, 1925. Serial No. 23,763. Divided and this application filed April 6, 1927. Serial No. 181,299.

This invention relates to brakes, and is illustrated as embodied in an internal expanding automobile brake. An object of the invention is to provide an inexpensive brake of the three-shoe type, suitable for light-weight cars, by taking the braking torque of all three shoes of the brake on a single anchor engaged by the secondary and auxiliary shoes.

10 Another feature relates to a novel arrangement giving a three-point support for the shoes against lateral movement, by the use of the anchoring means and a connection between the primary and secondary shoes, 15 taken with a novel cam between the primary and auxiliary shoes which is provided with a flange or plate or the like extending past the free ends of the primary and auxiliary shoes and engaging their sides.

20 Various other novel and desirable features of construction will be apparent from the following description of the illustrative embodiment of the invention shown in the accompanying drawing, in which:

25 Figure 1 is a vertical section through the brake, just inside the head of the drum, showing the brake shoes in side elevation;

Figure 2 is a partial section on the line 2—2 of Figure 1, showing the novel anchor-

30 age;

Figure 3 is a partial section on the line 3—3 of Figure 1, showing the connection between the primary and secondary shoes; and

Figure 4 is a section through one of the 35 shoes on the line 4—4 of Figure 1.

The brake selected for illustration includes a rotatable drum 10, at the open side of which is a suitable support such as a backing plate 12, and within which are arranged end to end primary, secondary, and auxiliary brake shoes 14, 16, and 18, each approximately 120° long, and which are illustrated as being stamped in channel form from sheet steel.

The channels of shoes 14 and 18 may be 45 slightly narrower than shoe 16, so that shoes 14 and 18 will project or "nest" in the ends of shoe 16. The adjacent ends of shoes 16 and 18 are provided with bushings 20 mounted on a single stationary anchor or pivot 22 carried by the backing plate 12.

At their adjacent ends (forming the second set of adjacent ends of the three shoes), shoes 14 and 16 are provided with bushings 24 mounted on a pivot 26 forming a floating connection between the shoes, and shown 55 with an enlarged head slidably engaging the backing plate 12 to position the shoe ends laterally. An auxiliary return spring 28 urges the enlarged head of pivot 26 toward an adjustable eccentric stop 30. 60

Between the third set of adjacent shoe ends, that is, between the free upper ends of shoes 14 and 18, there is arranged the applying device of the brake, illustrated as a double cam 32 acting against a return spring 34, 65 and provided with a part such as a flange or plate 36, which may be a separate piece held by a screw 38, and which projects past the shoe ends to engage the sides of the shoes to hold them laterally. 70

While one illustrative embodiment has been described in detail, it is not my intention to limit the scope of the invention to that particular embodiment, or otherwise than by the terms of the appended claims. 75 The present application is a division of my prior application No. 23,763, filed April 17, 1925, now Patent No. 1,630,059, dated May 24, 1927.

I claim:

1. A brake comprising, in combination, a drum, three shoes each approximately 120° in length and arranged end to end, a support for said shoe, and means for restraining the shoes against movement in one direction parallel to the drum axis including anchoring means for two adjacent shoe ends, a pivot connection for two other adjacent shoe ends and which is held against endwise movement at least in one direction, and applying means including a cam between the third set of adjacent shoe ends having at its end a part projecting past said third set of ends to hold them laterally. 85

2. A brake comprising, in combination, a drum, three shoes each approximately 120° in length and arranged end to end, a support for said shoe, and means for restraining the shoes against movement in the direction of the drum axis including anchoring means for 95

two adjacent shoe ends, a connection for two other adjacent shoe ends, and applying means including a cam between the third set of adjacent shoe ends having at its end a part 5 projecting past said third set of ends to hold them laterally.

3. A brake comprising, in combination, a drum, a plurality of shoes within said drum acting upon the same zone thereof, a support 10 for said shoes, together with means providing a three-point support for said shoes restraining the same against movement in a direction toward said support plate and substantially parallel to the drum axis, said support 15 means including (1) anchoring means for two adjacent shoe ends, (2) a pivot connection for two other adjacent shoe ends, and (3) means secured to an applying means positioned between and contacting the ends of a 20 third set of adjacent shoe ends.

In testimony whereof, I have hereunto signed my name.

ADIEL Y. DODGE.
